UNITED STATES PATENT OFFICE.

OSKAR SEITZ, OF BADEN, SWITZERLAND, ASSIGNOR TO GLEICHRICHTER-AKTIEN-
GESELLSCHAFT, OF GLARUS, SWITZERLAND.

VACUUM-METER.

Application filed August 29, 1921. Serial No. 496,261.

(GRANTED UNDER THE PROVISIONS OF THE ACT OF MARCH 3, 1921, 41 STAT. L. 1313.)

To all whom it may concern:

Be it known that I, OSKAR SEITZ, a citizen of the Swiss Republic, residing at Oberer Kappelerhof, Baden, Switzerland, have invented certain new and useful Improvements in Vacuum-Meters (for which I have filed application in Switzerland, Nov. 8, 1919, Patent No. 87,996; in Germany, Nov. 14, 1919, Patent No. 355,130; in France, Nov. 6, 1920; and in Belgium, July 4, 1921), of which the following is a specification.

This invention has for its object to provide an improved compression vacuum-meter of the McLeod type which is universally employed for measuring high vacua of the order of less than a millimetre of mercury.

This apparatus depends for its action on the compression to atmospheric pressure of a known volume of attenuated air contained originally in a measuring vessel including a capillary extension. The compression is carried out by means of a barometric column and the resultant volume is read off on the graduations of the capillary tube.

In such an apparatus, for the purpose of setting the elevated barometric mercury column relatively to the upper end of the capillary tube, (that is to say up to the line $y-y$ of Fig. 1 in the accompanying drawings) the vessel containing the store of mercury must be raised to a greater or less height according to the barometric height, and the mercury meniscus in the barometric tube must be visible.

For this reason those parts of the tubing in which the mercury meniscus moves are usually made of glass. However, in time a precipitate of finely subdivided mercurous oxide and metallic mercury is deposited on the wall of the barometric tube at the level of the $y-y$ line, so that the level of the mercury meniscus is no longer visible.

This is due to the fact that the mercury in the barometric tube is always under the vacuum of the receiver, and the deposition of the precipitate is promoted in a high vacuum. This does not occur so much in the capillary tube because in this tube the mercury is under higher absolute pressure than in the barometric tube so that, as found by experience, no disturbing deposit of precipitate has been found to take place in the capillary tube.

A vacuum-meter of the McLeod type is therefore influenced by atmospheric pressure both when at rest and when in measuring position, so that each reading requires a fresh and careful setting of the mercury meniscus. This necessitates the construction of the barometric tube of glass which, owing to its brittleness, is very liable to breakdowns. Further, for the purpose of cleaning, this tube from the aforesaid deposits it is necessary to have a special construction which is not favourable to reliability in the operation of the apparatus.

All these drawbacks are obviated by the improved form of vacuum-meter according to the present invention. The chief characteristic feature of this improved form consists in this that the barometric tube is provided at its upper end on a level with the top of the capillary tube, with an enlargement having a very large cross section in proportion to the cross section of the store of mercury that is in contact with atmospheric air. This arrangement has the result that the setting of the mercury store vessel which is requisite for a correct adjustment of the comparing mercury meniscus, is always independent of the height of the place of measurement above sea level and also always independent of the fluctuations in the atmospheric air pressure at said place.

An embodiment of this invention is illustrated in the accompanying drawings in which:

Fig. 1 is an elevation of the improved vacuum-meter in the position of rest.

Fig. 2 illustrates the apparatus in the measuring position, and

Referring to Fig. 1, the improved apparatus is composed of a barometric tube n which is provided at its upper end with an enlargement o and a connection s communicating with the vacuum to be measured. A capillary tube k provided with a reading scale and connected to a spherical enlargement m is fitted by means of a mercury stuffing box c into a branch i of the barometric tube. The surface of the mercury in the barometric tube which is in contact with the atmosphere consists of an annular surface formed by the fact that the lower end of the barometric tube is divided into two telescopically interfitting parts. The

outer tube which is vertically adjustable has an enlargement r that serves to contain the store of mercury.

By means of a rope pulley z with a hand crank drive, the tube r can be raised up to the stop a . The position of this stop a depends on the lowest sea level at which it is desired to take measurements.

The adjustment is effected relatively to 10 the axis $y-y$ and is determined by the mean barometric column corresponding to the respective sea level; it is also determined by the height p for taking into consideration the local variations in the barometric height, 15 and the height of the mercury store vessel r (measuring position shown in Fig. 2).

The position of the vessel r when the apparatus is at rest (as shown in Fig. 1) depends on the highest possible barometric 20 position. The position of the stop that is chosen from the above points of view must be retained once for all, independently of the sea level and the local variations in the height of the barometer at the place of use 25 of the apparatus.

When the apparatus, in the rest position shown in Fig. 1, is placed under high vacuum by means of its connection s , the barometric mercury column of, for instance, 30 730 millimetres is established. On raising the mercury vessel r from the position of rest shown in Fig. 1 into the measuring position shown in Fig. 2, through the distance h (which is given by the stop a) the mercury 35 rises up to the mark u at the level $y-y$ from the tube n into the enlargement o which has a large cross section f_2 and also into the bulb m and to a height in the tube k depending on the degree of vacuum under measurement, 40 compressing the gaseous content of the branch c, m, k into the upper part of k ; the mercury flowing out of the vessel r so that the bottom surface of mercury goes back to the annular surface f_1 comprised between 45 the inner and outer parts of the barometric tube.

The proportion between the areas of the two cross sections f_1 and f_2 is chosen such that any variations in the height of the mercury level in the vessel o such as may occur 50 in consequence of variations in the height of the barometer and the temperature or due to small losses of mercury, are so small as to be negligible. By this means all variations in the length of the mercury column in

the measuring position are transferred to the lower mercury level f_1 where they have no influence upon the measurement. The height of the vessel r above its rest position is therefore in all cases the same for the 60 measuring position so that instead of this adjustment being effected according to the upper level of the mercury as in the hitherto employed form of the apparatus, it can now, in the improved form, be effected in relation 65 to the stop a after the latter has been fixed once for all.

The upper mercury level can therefore be invisible and the barometric tube n together with the upper expansion vessel o and the 70 branch i may all be made of metal.

What I claim is:—

1. A vacuum meter of the McLeod type including a graduated capillary tube, a barometric tube communicating with the 75 capillary tube and having an enlarged bore at its upper end, a storage vessel surrounding the lower end of the barometric tube, the cross section of said enlarged bore being very great in proportion to the cross-section 80 of the space between the lower part of the barometric tube and the walls of the mercury storage vessel for the purpose of rendering the adjustment of the mercury storage vessel which is necessary for the proper 85 adjustment of the comparing mercury meniscus practically independent of variations of atmospheric pressure.

2. A vacuum meter as claimed in claim 1 in which the mercury storage vessel has an 90 internal cross-sectional area only slightly larger than the external cross-section of the barometric tube, the barometric tube being 95 slideable telescopically in said storage vessel.

3. A vacuum meter as claimed in claim 1 in which the mercury storage vessel has an 100 internal cross sectional area only slightly larger than the external cross section of the barometric tube, the barometric tube being slideable telescopically in said storage vessel, and a stop fixed relatively to the barometric tube and engageable with the storage vessel 105 for determining the upper limit of movement of said vessel.

4. A vacuum meter as claimed in claim 1, 110 having all its parts of metal with the exception of the graduated capillary tube.

In testimony whereof I have signed my name to this specification.

OSKAR SEITZ.
